UNITED STATES PATENT OFFICE.

FRANK J. BACKER, OF NEW CASTLE, PENNSYLVANIA.

CONVERTIBLE BAG.

Application filed November 22, 1923. Serial No. 676,323.

To all whom it may concern:

Be it known that I, FRANK J. BACKER, a citizen of the United States, residing at New Castle, in the county of Lawrence and State 5 of Pennsylvania, have invented certain new and useful Improvements in Convertible Bags, of which the following is a specification.

This invention relates to convertible receptacles for a multiplicity of purposes and has for its object the provision of a receptacle designed primarily for use for suspension upon a clothes line for holding clothes pins, or for use as a shopping bag, 10 15 the device being, however, capable of use in other capacities or for other purposes than those mentioned as there is no limitation whatever in this respect.

An important and more specific object is 20 the provision of a device of this character which has a peculiarly constructed and mounted handle which may be connected or disposed in different planes or positions, depending upon the use to which the receptacle is put.

An additional object is the provision of a convertible device of this character which will be simple and inexpensive in manufacture, easy to adjust or convert, efficient and 30 durable in service, and a general improvement in the art.

With the above and other objects and advantages in view, the invention consists in the combination and arrangement of the 35 several parts to be hereinafter more fully described and claimed and illustrated in the accompanying drawings in which:

Figure 1 is an elevation of the device showing it suspended from a line and in use 40 as a receptacle for clothes pins.

Figure 2 is an elevation at right angles to Figure 1.

Figure 3 is a front elevation of the device showing the parts arranged to form a shopping bag.

Figure 4 is an elevation at right angles to Figure 3.

Figure 5 is a detail view of the hoop.

Referring more particularly to the drawings, the numeral 10 designates a bag proper 50 which may be formed of cloth or any other flexible material and which may be made in any desired size and shape. The bottom of the bag is closed while its upper end is open 55 and formed with a hem 11 within which is located a draw-string 12 adapted to be

pulled for closing the open end. At a point spaced downwardly from its upper end the bag is formed with a hem 13 within which is located a hoop 14 of heavy gage wire, rod 60 or the like, which hoop is provided at spaced points with upwardly bent seats 15 for a purpose to be described.

At the top of the bag is a supporting structure which is preferably formed from 65 a single piece of wire as herein disclosed but which might of course be formed with more than one piece appropriately connected, or which might be formed of stock other than wire, though this material is highly desirable on account of its low cost. This support may be described as consisting of two upwardly extending V-shaped members which include upwardly converging outer arms 16 terminating in loops or eyes 17 engaged within the seats 15, and further including spaced parallel inner arms 18 twisted together at 19 and engaged about the hoop, as shown at 20. At their upper ends these V-shaped members are formed with 70 75 hooks 21 which are located at the junctures of the arms 16 and 18.

The relatively movable portion of the device comprises an adjustably or changeably mounted handle which is likewise preferably, though not necessarily, formed from a single piece of wire, rod or the like and which includes an elongated loop-like handle proper 22 having a V-shaped bottom portion 23, and having its upper portion merging into downwardly extending spaced parallel rods 24 which terminate in loops 25 slidably engaged upon the inner arms 18 of the V-shaped supporting members. The lower portion 23 of this handle 90 95 loop structure is offset with respect to the upper portion and is adapted to be engaged by the hooks 21 whereby to hold the handle member in a position relatively close to the open top of the bag.

When the device is used for containing clothes pins, the handle member is arranged as shown in Figures 1 and 2, the hooks 21 being engaged upon the lower portion 23 of the handle loop proper. The V-shape of 100 this portion prevents the hooks from slipping laterally so that their proper position will be effectually maintained. Prior to the engagement of the hooks upon the member 23, the loop of the handle is engaged over 110 the clothes line, indicated by the letter A, so that the device will be suspended in such

a way that it may be slid freely along the line from place to place where its use is desired. When the device is employed in this capacity the draw-string 12 is loosened so that the top of the bag will be open and the free upper end is tucked down into the bag so as to be out of the way. It should be observed that the draw-string is preferably arranged with its loops engaged about the outer arms 16 so that they may be always in such position as to be easily grasped and pulled.

When the device is employed as a shopping bag it is of course removed from the clothes line, the free upper end of the bag is pulled out so as to extend above the hoop 14, and the hooks 21 are disengaged from the bottom portion 23 of the handle loop, the handle member consequently moving upwardly or away from the bag with the loops 25 engaging beneath the inner sides of the hooks 21, as indicated in Figures 3 and 4. The loop 22 serves as convenient carrying means inasmuch as any desired number of fingers may be engaged therein.

From the foregoing description and a study of the drawings, it will be apparent that I have thus provided a simply constructed, inexpensive and readily convertible bag or receptacle which is bound to be convenient in use and which, on account of its simplicity, should recommend itself to those having occasion to employ its services.

While I have shown and described the preferred embodiment of my invention, it is of course to be understood that I reserve the right to make such changes in the form, construction and arrangement of parts as will not depart from the spirit of the invention or the scope of the subjoined claims.

I claim:

1. In a device of the character described, a receptacle, hooked supporting means mounted upon and projecting above the receptacle, and a handle member movably mounted upon said supporting means and engageable with the hooks whereby to be held stationary, said handle member being adapted for engagement over a line whereby to suspend the receptacle therefrom.
2. In a device of the character described, a receptacle, hooked supporting means mounted upon and projecting above the receptacle, and a handle member movably mounted upon said supporting means and

engageable with the hooks whereby to be held stationary, said handle member being adapted for engagement over a line whereby to suspend the receptacle therefrom, and means carried by the handle member at the lower end thereof and engageable with the hooks of the support for suspension of the receptacle at a lower level.

3. In a device of the character described, a receptacle, upwardly converging inverted V-shaped supports connected with the receptacle and provided with hooks at their upper ends, a handle member slidably connected with said supports, and means engageable with the hooks for holding the handle member at a selected position.

4. In a device of the character described, a receptacle, upwardly converging inverted V-shaped supports connected with the receptacle and provided with hooks at their upper ends, a handle member slidably connected with said supports, and means engageable with the hooks for holding the handle member at a selected position, the handle member including a portion adapted selectively to be engaged over a flexible support or to constitute a handle proper.

5. In a device of the character described, a receptacle, a hoop forming a part thereof, a pair of upwardly extending supports carried by the hoop and including spaced parallel arms and further including hooks at their upper ends, and a handle member including a loop portion and spaced depending rods terminating in eyes slidable upon said arms, said eyes and the bottom portion of the loop being selectively engageable with the hooks.

6. In a device of the character described, a receptacle, a spreader carried thereby, a hook member permanently connected with the spreader and including guides, and a handle slidably mounted on the guides and having a keeper portion adapted to be engaged with the hook member.

7. In a device of the character described, a receptacle, a support connected therewith and including a central guide portion and hooks at opposite sides thereof, and a handle slidably upon the guide portion and having a retaining portion detachably engageable with the hooks.

In testimony whereof I hereto affix my signature.

FRANK J. BACKER.
